UNITED STATES PATENT OFFICE.

WILBUR F. DAY, OF ST. PAUL, MINNESOTA.

BURNER.

1,310,066.

Specification of Letters Patent. Patented July 15, 1919.

Application filed January 20, 1919. Serial No. 272,035.

To all whom it may concern:

Be it known that I, WILBUR F. DAY, a citizen of the United States, resident of St. Paul, county of Ramsey, State of Minnesota, 5 have invented certain new and useful Improvements in Burners, of which the following is a specification.

The object of my present invention is to provide a supporting means for the flame deflector which will aid in vaporizing the liquid fuel in the generator.

A further object is to provide improved means for supplying moisture to the burner flame to promote combustion.

15 A further object is to provide means for directing any overplus of oil entering the retort and dripping through the air admission chamber back to the priming pan.

Other objects of the invention will appear from the following detailed description.

The invention consists generally in various constructions and combinations, all as hereinafter described and particularly pointed out in the claims.

25 In the accompanying drawings forming part of this specification,

Figure 1 is a side elevation, partially in section, of a burner embodying my invention,

30 Fig. 2 is a plan view of the same, also partially in section,

Fig. 3 is a sectional view on the line 3—3 of Fig. 1,

Fig. 4 is a sectional view through the pipe 35 supporting the deflector plate,

Fig. 5 is a plan view of a modified construction.

In the drawing, 2 represents the base of the burner, adapted to be seated on the stove 40 grate within the fire-box, as usual in burners of this type and as particularly shown and described in my U. S. Patent issued May 16, 1916, No. 1,181,748.

The burner shown in Fig. 1 is of the double type, with a generating chamber or retort at each end of the base. I will therefore describe the one shown in section indicating the corresponding parts of the other retort with the same reference numerals.

50 3 represents a member, preferably tubular in form, comprising an air admission chamber of the burner and having recesses 4 in its upper walls to receive the pipe section 5 of the retort or generator. This retort may be of any suitable metal, shown here as cast, comprising an outer part 6, substan-

tially oval in form and having a passage 7 therein with the part 5 bridging the opening of the part 6 and integrally joined therewith at the ends. The part 6 is substantially a hollow ring and at a point opposite the passage leading to the part 5 is provided with an opening and a nipple 8 for connection with a coupling 9 in the base, said coupling having a pipe 10 for communication 60 with a source of liquid fuel supply, not shown. The other side of the part 6 adjacent the opposite end of the bridging member 5 is tapped to receive a goose-neck pipe 11 which extends upwardly and has a horizontal part 12 overhanging the burner, the end of the pipe being closed by a suitable cap 13. On this horizontal part 12 a deflector plate 14 is loosely mounted for adjusting back and forth on the pipe and being positioned over the middle portion of the part 5, and the chamber 3 operates as a deflector for the flame of the burner. The direct passage through the bridging part 5 is closed by a plug 15 and the upper wall of this part 70 has a centrally arranged port 16 which forms the nozzle of the burner. Extending around the member 3 is a priming pan 17 in which a quantity of the liquid fuel may be placed and ignited. The walls of the generator will thereby be heated until a sufficiently high temperature is obtained to vaporize the oil delivered to the generator and this vapor ignited at the nozzle 16 will supply the flame for the burner.

As the liquid fuel flows through the pipe 10 and enters the hollow ring-like member 6, it will flow in opposite directions through the sections of this member around to the entrance of the part 5 and then will flow 95 down this part to the nozzle 16. During this flow the fuel will be vaporized and the part 12 of the pipe 11 will be heated to a very high degree by the flame of the burner and the transmission of the heat through the 100 metal and the radiation from the pipe 11 will provide a more intense heat in the generator to assist vaporization. This pipe has therefore two functions. It aids in vaporizing the liquid fuel and also forms a support for 105 the deflector plate.

It sometimes happens that an excess of oil will be delivered to the generator and before it becomes sufficiently hot to vaporize a portion of this oil may escape through the 110 nozzle and would ordinarily drip down through the chamber 3 into the base of

the stove. To avoid this waste, I provide a bridge 18 extending across from wall to wall of the chamber 3 and curved in cross section to form a trough, which is preferably inclined, the wall of the chamber having a port 19 therein communicating with the discharge end of the trough so that such excess liquid falling into the trough will flow therefrom through the port 19 into the priming chamber.

I also prefer to provide a water chamber 20 on the base of the burner between the chamber 3 with a supply pipe 21 communicating therewith and having a suitable regulating valve (not shown). This pipe 21 may be supplied by gravity or pressure, as preferred. By opening the valve a supply of water to the desired depth may be maintained in the water chamber. When the burner is in use, evaporation will take place in this chamber and the air charged with moisture will flow up around and into the flame of the burner and produce a better combustion and more intense heat.

In Fig. 5 I have shown a modified construction in which a circular burner 23 is provided, encircled by a circular priming pan 24. The air admission chamber, also preferably circular in form, indicated by reference numeral 3, is encircled by the generator and corresponds substantially in its general construction to the one shown in the previous figures. This Fig. 5 also illustrates the horizontal pipe section 12 supporting the flame deflector 14. A water pan 20^a, circular in form, encircles the priming pan.

It will be noted that the generator can be easily removed from the burner by merely detaching the coupling 9 which permits the nipple 8, the generator and the pipe 11 to be lifted clear of the wall of the air admission chamber.

I have shown the pipe 11 extending lengthwise of the burner base along the center line thereof, but do not confine myself to this position, as it may be arranged in any other suitable position.

I claim as my invention:

1. A liquid fuel burner comprising a base, an air admission chamber mounted thereon, a priming pan encircling the walls of said chamber, a vapor generator seated on said chamber, a coupling removably connecting said vapor generator with a liquid fuel supply pipe, said generator comprising an outer hollow ring portion, an intermediate hollow portion bridging the opening in said ring and communicating at one end therewith, and at its opposite end with said supply pipe coupling, said intermediate portion having a nozzle opening in its upper walls and means for closing the passage through said intermediate portion between said nozzle and said supply pipe opening.

2. A liquid fuel burner comprising a base,

an air admission chamber supported thereon and having recesses in its upper walls, a liquid generator comprising a hollow ring-like portion encircling the upper walls of said generator and having an intermediate portion bridging the opening in said ring-like portion and seated in the recesses in said chamber walls and communicating with the passage in said ring-like portion, a liquid fuel supply pipe communicating with said passage at one end of said intermediate portion and said intermediate portion having a nozzle opening in its upper walls, and means for closing the passage through said intermediate portion between said nozzle and said supply pipe.

3. A liquid fuel burner comprising a base, an air admission chamber mounted thereon, a liquid fuel generator in the form of a hollow ring removably seated on said chamber and having a fuel nozzle in its upper walls, and a liquid fuel supply pipe and coupling therefor connecting it with said generator.

4. A liquid fuel burner comprising a base, an air admission chamber mounted thereon, a liquid fuel generator in the form of a hollow ring encircling said chamber and having a connection for a liquid fuel supply pipe and a nozzle in the upper wall of said generator, a hollow goose neck mounted on said generator and having a part overhanging said generator for heating the same, and a deflector plate carried by said gooseneck.

5. A liquid fuel burner comprising a base, an air admission chamber mounted thereon, a liquid fuel generator encircling said chamber and having a hollow portion bridging the opening in said generator and communicating at one end therewith, said hollow portion having a nozzle in its upper wall and a hollow goose neck communicating with said generator and having a part overhanging said nozzle.

6. A liquid fuel burner comprising a base, an air admission chamber mounted thereon, a liquid fuel generator arranged near the upper portion of said chamber, and having an opening therein, a hollow member bridging the opening therein and provided with a nozzle in its upper wall, and a connection for a liquid fuel supply pipe, means directing the flow of the fuel through the circular portion of said generator before reaching said bridging member, and a hollow goose neck mounted on said generator and communicating therewith and having a part overhanging said nozzle.

7. A liquid fuel burner comprising a base, and air admission chambers mounted thereon, liquid fuel generators adjacent said mixing chambers and having connections for liquid supply pipes, and flame nozzles in the upper walls of said generators and a water

100

105

110

115

120

130

pan formed on said base between said chambers and adapted to contain a supply of water.

8. A liquid fuel burner comprising a base, 5 an air admission chamber formed thereon and a priming pan encircling the walls of said chamber, a liquid fuel generator encircling the upper portion of said chamber and in the form substantially of a hollow 10 ring, a nipple connecting one side of said generator with an opening in the floor of said priming pan, and a coupling connecting said nipple with a liquid fuel supply pipe, said generator being separable from 15 said chamber when said nipple is disconnected from said coupling.

9. A liquid fuel burner comprising a base, an air admission chamber mounted thereon, a vapor generator above said chamber comprising an outer hollow ring portion, an intermediate hollow portion bridging the opening in said ring, a liquid fuel supply pipe communicating with said ring portion, said intermediate hollow portion 20 having a nozzle opening in its upper wall, said nozzle opening communicating with said ring through the end of said hollow portion remote from said liquid fuel supply pipe, and means for closing the passage 25 through said intermediate portion between said nozzle and the other end of said hollow portion.

10. A liquid fuel burner comprising a base, an air admission chamber mounted 35 thereon, a liquid fuel generator in the form of a hollow circular member above said chamber and having a connection for a liquid fuel supply pipe and provided with an opening and a hollow member bridging 40 said opening and connected at each end with the generator, and having a nozzle in its upper wall and a hollow goose neck mounted on said generator and overhanging said generator for heating the same.

45 11. A liquid fuel burner comprising a base, an air admission chamber mounted thereon, a priming pan at the base of said chamber, a hollow ring-shaped generator

near the upper portion of said chamber, a hollow member bridging said generator and 50 having a vapor nozzle in its upper wall, a trough bridging said chamber below said nozzle to receive the oil drippings therefrom, the wall of said chamber at the discharge end of said trough having a port 55 therein leading from said trough to said priming pan.

12. A liquid fuel burner comprising a base and air admission chambers mounted thereon, vapor generators above said chambers comprising outer hollow ring portions and intermediate hollow portions bridging the openings in said rings and communicating at the ends therewith and with liquid fuel supply pipes, said intermediate portions 60 having nozzle openings in their upper walls and means for closing the passages through said intermediate portions between said nozzles and said liquid fuel supply pipes. 65

13. A liquid fuel burner comprising a base and air admission chambers mounted thereon, liquid fuel generators adjacent said air admission chambers and having connections for liquid supply pipes and flame 75 nozzles in the upper walls of said generators, a water pan formed on said base between said air admission chambers and adapted to contain a supply of water, and 80 goose necks mounted on said generators and extending inwardly and upwardly over said water pan and having horizontal upper portions overhanging the flame nozzles of said generators.

14. A liquid fuel burner comprising a 85 base, an air admission chamber mounted thereon, a liquid fuel generator arranged near the upper portion of said chamber and in the form substantially of a hollow ring, and a hollow member bridging the 90 opening in said ring and provided with a nozzle in its upper wall and a liquid fuel supply pipe communicating with said ring.

In witness whereof I have hereunto set my hand this 15th day of January, 1919.

WILBUR F. DAY.
